UNITED STATES PATENT OFFICE.

JEAN LOUIS THOMAS THUROT, OF PARIS, FRANCE, ASSIGNOR TO SOCIÉTÉ DES CARBURATEURS THUROT (THUROT, MEYER & CIE.), OF PARIS, FRANCE.

CARBURETER.

1,158,589.

Specification of Letters Patent.

Patented Nov. 2, 1915.

Application filed December 19, 1913. Serial No. 807,677.

To all whom it may concern:

Be it known that I, JEAN LOUIS THOMAS THUROT, a citizen of the Republic of France, and resident of Paris, France, have invented 5 a new and useful Carbureter, which carbureter is fully set forth in the following specification.

This invention relates to a carbureter in which the manipulation of a handle operating 10 a plug to open or close air inlet openings communicating with jets or sprayers, one of which is below the constant level of the liquid fuel and is consequently flooded, enables the supply of gaseous mixture to be 15 regulated in proportion to the running of the engine.

The invention further relates to a construction of the carbureter in which, while the system of sprayers and the plug are retained, the arrangement and the method of securing the sprayers relatively to the carbureter, have been modified for the purpose of simplification.

In order to make the following explanation as clear as possible, the accompanying drawings show by way of example, a carbureter according to this invention.

Figure 1 is a vertical section on line A—A of Fig. 2, Fig. 2 is a plan view, Fig. 3 is a 30 vertical section on line B—B of Fig. 2.

The constant-level fuel tank *a*, (Figs. 1, 2 and 3), which, incidentally, presents no special features, communicates by means of a conduit 1 and a collector 2, with three 35 branches 3, 3' and 3'' terminating in sprayers or jets 4, 4' and 4'', occupying the centers of orifices 5, 5' and 5'' in the casing *b* of the carbureter. Owing to its low position the sprayer 4'' is flooded, the liquid 40 fuel reaching its level in a cup 6. The casing *b* is provided with a main air passage 7 corresponding to the orifice 5', and with two other air passages 8 and 9 corresponding 45 respectively to the orifices 5 and 5'' and opening into the main passage 7 behind the plug 10, the passage 8 being constantly open. The plug 10 is formed with a central butterfly 11 which controls the main passage 7, and with an end passage 9' which is 50 designed to establish communication between the said passage 7 and the passage 9, as shown in Fig. 1. The plug 10 is operated by means of an exteriorly-located handle 12. The passage 9 is made in a bell 13 surround- 55 ing the cup 6, and the position of the said

bell can be modified by screwing or unscrewing it, so as to regulate the quantity of air admitted.

For running at slow speed, the plug 10 is turned by means of the handle 12 into the 60 position shown in Fig. 3, in which the butterfly 11 completely closes the passage 7, and the port 9' does not coincide with the passage 9. Under these conditions, the gaseous mixture which is drawn into the engine 65 by the suction exerted through the passages 7 and 8, is formed only by the air passing through the restricted orifice 5 and carbureted on contact with the liquid fuel discharged through the sprayer 4. For a 70 higher speed of the engine, the plug 10 is brought into the position shown in Fig. 1, in which the butterfly 11 still closes the passage 7, but the port 9' coincides with the 75 passage 9, so that to the quantity of gaseous mixture drawn through passage 8, is added the mixture produced by the air which under the suction action of the engine, passes under the bell 13 and between the walls of the said bell and those of the cup 6 in order to be carbureted in passing through the liquid occupying said cup. For running at 80 normal speed, the plug 10 is turned so that the butterfly 11 uncovers the passage 7, and the sprayer 4' supplies fuel so as to carburet 85 the air drawn through the maximum orifice 5'.

I claim—

1. In a carbureter for internal-combustion engines, the combination, with a casing having a main air-supply passage, and a pair of auxiliary air-supply passages located at opposite sides of and communicating with said main passage, one of said auxiliary passages being constantly open, of a series of three sprayers projecting into said passages; a constant-level fuel-supply tank in communication with said sprayers, one of the sprayers being located below the level of the said fuel; and a plug valve rotatably mounted in said casing and provided with an end port controlling the other auxiliary passage and with a central butterfly controlling said main passage, the arrangement being such that the first named auxiliary passage is open during running of the engine at slow speed, the port opening the other auxiliary passage for higher speed, and the butterfly opening for normal speed.

2. In a carbureter for internal-combustion

engines, the combination, with a casing having a main air-supply passage, and a pair of auxiliary air supply passages located at opposite sides of and communicating with said main passage, one of said passages being constantly open, of means for spraying liquid fuel into said passages for admixture with the air admitted thereinto; and a plug valve rotatably mounted in said casing and provided with an end port and with a central butterfly controlling the other auxiliary passage and the main passage, respectively, the arrangement being such that the first-

named auxiliary passage is open during running of the engine at slow speed, the 15 other auxiliary passage port opening for higher speed, and the butterfly opening for normal speed.

In testimony whereof I have signed this specification in the presence of two subscribing witnesses.

JEAN LOUIS THOMAS THUROT.
